Attorney

UNITED STATES PATENT OFFICE

JOHN LEE MAULDIN, OF PETTUS, TEXAS

HIGH PRESSURE PUMP

Application filed June 16, 1930. Serial No. 461,445.

This invention relates to improvements in high pressure pumps, and the objects of the present invention are, first to enable drillers of wells to blow plugs out of plugged bits; second to test casing (pipe) and ascertain if there be a leak or leaks therein; third, to test the seat of casing (pipe) and ascertain if there be an escape of water after cement plugs have been drilled out; fourth to obtain returns (circulation of mud) on stuck casing or drill stem (pipe) when returns are not obtainable by low pressure pumps; fifth, to plug a well or kill a well; sixth to pull casing (pipe); and seventh, to serve other high pressure needs.

Other objects and advantages of the invention will become apparent during a study of the following description, taken in connection with the accompanying drawing, wherein:

Figure 1 is an elevational view of my improved pressure pump,

Figure 2 is a longitudinal sectional view therethrough,

With reference more in detail to the drawing, it will be seen that my improved pressure pump comprises an open ended cylinder 5 normally closed at one end through the medium of a nipple 6, which nipple is also closed at its upper end as at 8. The nipple is secured to the lower end of the cylinder 5 through the medium of an internally threaded collar 9 threadedly connected to said lower end of the cylinder 5 and the upper end portion of the nipple 6. The upper end of the cylinder 5 is normally closed through the medium of a suitable cap 9 provided with an annular flange or skirt internally threaded for threaded engagement with the upper end of the cylinder 5 as at 10.

Mounted for reciprocation within the cylinder 5 is a piston 11, the same at its upper end being reduced as at 12. The reduced portion 12 forms on the upper portion of the piston an annular shoulder and together follower plate 14 retains about the upper reduced portion of the piston 11 a suitable packing 13. The piston rod is designated by the reference character 15, and at

its lower end the said piston rod is provided with a relatively thick externally threaded portion threaded within the piston 11, and at its lower end has a suitable nut 17 threaded thereon. A lock nut 18 is threaded on the upper end portion of the threaded end 16 of said piston rod for bearing against the plate 14 to retain the latter in position.

A nipple 19 has its upper closed end threaded in the lower end of the cap 9 axially of the cap and the piston rod 15 extends through the nipple 19 and the cap 9 to project beyond the upper end of the cap through a suitable stuffing box arrangement formed in the cap 9 as at 21. The nipple 19 is suitably threaded in the cap 9 as at 20. Convolute about the piston rod 15 is a coil spring 22, one end of which bears against the lock nut 18, and the upper end of which bears against the upper closed end of the nipple 19 for normally urging the piston 11 downwardly or toward the lower end of casing 5.

The upper extended end of the piston rod 15 has suitably secured thereto a bail 23 normally engaged by a hook 24 suspended from a suitable travelling block designated generally by the reference character 25.

The reference character G designates a pressure gauge having communication with the interior of the nipple 6 through the medium of a suitable supporting pipe 26 threaded at one end in the walls of the nipple. The nipple is also provided externally thereof with a suitable pressure release valve 27.

The cylinder 5 adjacent the top and bottom thereof is also provided with upper and lower pet cocks 28 and 28' respectively. Leading into the upper end of the cylinder 5 is a suitable intake pipe 29 having arranged therein a check valve 30.

Leading from the upper end portion of the cylinder 5 to the nipple 6 at opposite sides of the cylinder 5 and nipple 6 are by-passes designated generally by the reference characters 31 and 32 respectively. Each of the said by-passes include a pipe 33 leading from one side of the nipple 6 and coupled at its free end through the medium of an elbow 34 to a riser pipe 35. Arranged in

the riser pipe 35 is a gate valve 36. Above the gate valve 36 and also arranged in the riser 35 is a check valve 37.

The upper end of the riser 35 is suitably coupled to a pipe section 39 through the medium of a union 38. The pipe section 39 in turn is coupled to a pipe 41 leading into the upper end of the cylinder 5 through the medium of a suitable elbow 40.

10 The operation of my improved pressure pump is as follows: The pump is to be fitted in a casing or drill stem within a well.

Water is then pumped through the intake pipe 29 and check valve 30 into the cylinder 5. Power from an engine (not shown) is to be applied through the travelling block 25 to move the piston 11 upwardly of the cylinder 5 against the action of the spring 22. As the said piston ascends, with the accumulation of water above it, the water will be forced through the by-passes 31, 32, into the nipple 6, thus filling said nipple and adding to the contents of the well casing and thus developing enough pressure to accomplish the object in view whether that object be to blow the plugs out of plugged bits; to test the well casing for ascertaining whether or not there be a leak or leaks therein, or to test the seat of the casing and ascertain if there be an escape of water after cement plugs have been drilled out. Again it may be to obtain returns (circulation of mud) on stuck casing or drill stem when returns are not obtainable by low pressure pumps or again it may be the provision of pressure to plug a well or kill a well, or perhaps to pull the well casing or lastly for any other such purposes for which pressure in the well casing is desirable. In the operation of the device 40 water forced into the nipple 8 is prevented from turning through the by-passes 31 and 32 to the casing by the check valve arranged in each of the said by-passes.

Obviously the pressure resulting is registered on the pressure gauge. Any excess pressure may be released through the pressure release valve 27 of the nipple. Also air within the cylinder 5 may be released through the pet cocks 28 and 28'.

50 Even though I have herein shown and described the preferred embodiment of my invention, it is to be understood that the same is susceptible to changes fully comprehended by the spirit of the invention as herein described, and the scope of the appended claim.

Having thus described my invention, what I claim as new is:

60 In a pressure pump of the class described, a cylinder opened at its lower end, a nipple having a closed end normally closing the opened end of said cylinder, means coupling one end of the nipple with an adjacent end of the cylinder, said nipple being provided with an outlet, a valved conduit connecting one side of the nipple with one side of the

cylinder adjacent the upper end of the cylinder, a second valved conduit connecting the opposite side of the nipple with the corresponding side of the cylinder adjacent the upper end of the cylinder, a piston mounted for reciprocation in said cylinder, spring means normally urging the piston toward the lower end of the cylinder, a rod for said piston extending outwardly through the top of the cylinder, said rod at its free end adapted to be coupled to a suspension element, and said cylinder provided with a valved inlet adjacent the top thereof.

In testimony whereof I affix my signature.

JOHN LEE MAULDIN.
